UNITED STATES PATENT OFFICE.

GEORGE V. TUCKER AND EDWARD B. AIGUIER, OF NEWARK, NEW JERSEY, ASSIGNORS TO RICHARDSON MANUFACTURING COMPANY, OF NEWARK, NEW JERSEY.

STOCK-COLLAR DISTENDER.

No. 807,884.

Specification of Letters Patent.

Patented Dec. 19, 1905.

Application filed October 2, 1905. Serial No. 281,012.

To all whom it may concern:

Be it known that we, GEORGE V. TUCKER and EDWARD B. AIGUIER, citizens of the United States, and residents of Newark, in the county 5 of Essex and State of New Jersey, have invented a new and Improved Stock-Collar Distender, of which the following is a full, clear, and exact description.

This invention relates to improvements in 10 devices for distending vertically and supporting so-called "stock-collars" worn by women, the object being to provide a device for this purpose of simple and novel construction for detachable connection with the stock and used 15 in lieu of whalebones, wires, or the like, so that after removing the distenders the stock may be readily washed or otherwise cleaned.

Another object is to so arrange the fastening devices that they cannot become detached 20 and lost.

We will describe a stock-collar distender embodying our invention and then point out the novel features in the appended claims.

Reference is to be had to the accompanying 25 drawings, forming a part of this specification, in which similar characters of reference indicate corresponding parts in all the figures.

Figure 1 is a perspective view of a stock-distender embodying our invention. Fig. 2 30 is a side view thereof, showing the same as engaging with the sections of a stock; and Fig. 3 is a rear view of the device, parts being shown in section.

The device comprises tubular body members 35 1 2, one of which has interior right and left hand screw-threads. These body members are connected by a cross bar or brace 3, the said bar being rigidly clamped to one body member, while the member having the 40 interior threads is slidable through the bar. This cross-bar, it will be understood, may be omitted without departing from the spirit of our invention; but it will serve in a great measure to prevent lateral strain or movement of the body portions one relatively to the other.

Having movable or sliding connection with the body members 1 2 are the stock-engaging devices 4 5, each device consisting of a wire 50 or the like bent to substantially U form. One section or member 6 of the part 4 is here shown as rigidly secured in the tubular body member 1, while the other member 7 has a

screw-thread for engaging with the thread in the tubular body member 2. The engaging 55 device 5 has one member 8 screw-threaded to engage with the thread in the member 2, while the other member 9 is slidable in the tubular body member 1.

On each sliding member at the end is a loop 60 10, one of which is designed to engage over the upper edge of the stock, while the other is to engage around the lower edge of the stock. Each loop 10 is provided with a threaded socket member 11, in which a fastening-screw 12 engages. The outer end of each fastening-screw is provided with a button or finger-piece 13, and to prevent the fastening-screws from being wholly removed from the socket members the inner ends of the screws 70 are provided with collars 14.

In operation it is to be understood that two or more of these devices will be employed. The tubular body portion and the sliding members are arranged at the inner side of the 75 stock, while, as before stated, the loops pass over or around the upper and lower edges of the stock, so that the collars 14 on the screws will engage and clamp against the stock material. By turning the threaded tubular member 2 it is obvious that the collar-engaging devices may be moved outward to distend the stock. By providing the loops 10 it is obvious that the clamping-screws need not pass through or puncture the material of the stock, 85 as is necessary with other devices of a somewhat similar nature. It is obvious that one of the collar-engaging devices may have its branches or members rigidly secured to the two body-tubes, the other one being slidable. 90

Having thus described our invention, we claim as new and desire to secure by Letters Patent—

1. A device for the purpose specified, comprising two tubular body portions, collar-engaging devices having sliding connection with said body portions, curved loops on the ends of said collar-engaging devices, and clamping-screws for operating in said loops. 95

2. A device for the purpose specified, comprising two tubular body portions, one of said body portions having right and left interior screw-threads, collar-engaging devices at the ends of the body members, each consisting of two connected sections, a section of each being screw-threaded for engaging with the 100 105

thread in the tubular body member, the other member of one of the engaging devices being 5
slidable in the other tubular body member, curved loops on the ends of said sliding de-
vices, the said loops having tapped socket
members, and clamping-screws engaging in
said socket members and having enlarged in-
ner ends.

3. A device for the purpose specified, comprising two tubular body members, a cross- 10
bar rigidly connected to one of the body mem-
bers and through which the other body mem-
ber is slid able, the said slide able member be-
ing interiorly screw-threaded, substantially
15 U-shaped collar-engaging devices, one mem-
ber of each collar-engaging device being
threaded to engage the thread within said slide-

able body member, loops on the ends of said
sliding collar-engaging devices, and clamping-
screws operating in said loops. 20

4. A device for the purpose specified, comprising members for engaging over the up-
per and lower edges of a stock, means for
clamping said portions to the stock, and
means for moving said portions toward and 25
from each other.

In testimony whereof we have signed our
names to this specification in the presence of
two subscribing witnesses.

GEORGE V. TUCKER.
EDWARD B. AIGUIER.
